UNITED STATES PATENT OFFICE.

CHARLES W. HILL, OF POWELL, WYOMING.

WRENCH.

Application filed April 30, 1924. Serial No. 710,065.

To all whom it may concern:

Be it known that I, CHARLES W. HILL, a citizen of the United States, residing at Powell, in the county of Park, State of Wyoming, have invented certain new and useful Improvements in Wrenches; and I do hereby declare the following to be a full, clear, and exact description of the invention, such as will enable others skilled in the art to which it appertains to make and use the same.

This invention relates to new and useful improvements in wrenches.

One object of the invention is to provide a wrench wherein the sliding jaw is automatically forced against the work upon the proper working movement of the wrench.

Another object is to provide a wrench wherein the movable jaw is capable of coarser adjustment toward the work, and wherein the finer adjustment is automatic upon the active operation of the wrench.

Other objects and advantages will be apparent from the following description when taken in connection with the accompanying drawing.

In the drawing:

Figure 1 is an elevation of a wrench made in accordance with the present invention; and

Fig. 2 is a longitudinal sectional view through the sliding jaw, showing the action of the lock, the shank of the wrench being in elevation.

Referring particularly to the accompanying drawing, 10 represents the shank of the wrench which is formed with the outer fixed jaw 11, provided with the teeth 12 on its operating face, and with the teeth 13 on the edge face of the shank. Slidable on the shank is a block 14, which has the two loops 15 and 16 disposed in embracing relation to the shank, the loop 16 being slightly longer than the loop 15, whereby to permit vertical rocking movement of the block toward and away from the shank. In the lower face of the block 14, directly above the toothed edge of the shank, there is formed a recess 17, the forward end wall 18 of which inclines toward the operating face of the block, and in the direction of the toothed face of the shank. Disposed within this recess is a block 19, having its lower face formed with teeth 20 for interlocking engagement with the teeth of the shank, and having its forward end beveled or inclined,

as shown at 21, for sliding engagement with the inclined wall 18 of the recess. A coil spring 22 is secured, at one end, in the upper rear portion of the block 19, and at its other end in the upper rear end of the recess 17, said spring exerting a pressure against the block longitudinally of the shank, in the direction of the fixed jaw, and downwardly to engage its teeth with the teeth of the shank. When the block 14 is pressed along the shank, in the direction of the fixed jaw, the teeth of the block 19 will slide over the teeth of the shank, and by engagement of these teeth, the backward movement of the block 14 is prevented. However, upon the operator grasping the opposite sides of the block 19, said block may be moved upwardly in the recess 17, until the teeth are free from the teeth of the shank, thereby permitting the movement of the block 14 along the shank, in a direction away from the fixed jaw.

In the operation of the wrench the jaws are positioned on opposite sides of the work, the movable jaw block 14 being moved up until its working face engages with the work. The inclined face of the block 19 will be engaged with the inclined face or wall 18, of the recess 17, so that when the operator grasps the handle portion of the shank and moves same in the act of rotating the work, the forward end portion of the block 14 will be forced inwardly toward the shank of the wrench, and upon such movement the inclined wall 18 will slide on the inclined face 21, with the result that the block 14 will move forwardly into firmly gripping engagement with the work. The teeth of the block 19, being firmly interlocked in the teeth of the shank, the said block will be held against movement longitudinally of the shank, whereby the forward movement of the sliding jaw is assured.

By this construction the coarser adjustment of the sliding jaw is accomplished by pushing same forwardly toward the work, but the finer adjustment is accomplished automatically when the wrench is brought into operation to turn the work.

What is claimed is:

In a wrench, a toothed shank, a fixed jaw integral with said shank at one end thereof, a slideable jaw embracing said shank by means of spaced loop members providing a recess in proximity to the teeth of the shank, an inclined end wall disposed inwardly

toward the shank and longitudinally of the fixed jaw, and a toothed block having an inclined face for sliding movement in said recess and along said inclined end wall, 5 whereby the slidable jaw is simultaneously forced toward the shank and in closer proximity to the fixed jaw to enable the work to

be more firmly gripped upon operative movement of the wrench with respect to the work.

In testimony whereof, I have affixed my signature.

CHARLES W. HILL.
